[57] CLAIM

The ornamental design for a sun shield having a tilt-up visor,
as shown and described.

DESCRIPTION

FIG. 1 is a front elevational view of a sun shield having a
tilt-up visor which forms my invention;

FIG. 2 is a rear elevational view thereof;

FIG. 3 is a left side elevational view thereof; the side
opposite being a mirror image;

FIG. 4 is a top plan view thereof;

FIG. 5 is a bottom plan view thereof; and,

FIG. 6 is a left side elevational view thereof with the sun
shield having a tilt-up visor in the raised up position, the
broken line showing of the human face is for illustrative
purposes only and forms no part of the claimed design.
